UNITED STATES PATENT OFFICE.

HENRY H. EATHERTON, OF CISCO, ILLINOIS, ASSIGNOR OF ONE-HALF TO
ASA C. THOMPSON, OF SAME PLACE.

TILE-DITCHER.

SPECIFICATION forming part of Letters Patent No. 279,141, dated June 12, 1883.

Application filed March 24, 1883. (No model.)

To all whom it may concern:

Be it known that I, HENRY H. EATHERTON, of Cisco, in the county of Piatt and State of Illinois, have invented certain new and useful 5 Improvements in Tile-Ditchers; and I do hereby declare that the following is a full, clear, and exact description of the invention, which will enable others skilled in the art to which it appertains to make and use the same, reference 10 being had to the accompanying drawings, which form a part of this specification, and in which—

Figure 1 is a perspective view of my improved tile-ditcher. Fig. 2 is a longitudinal vertical section of the same. Fig. 3 is a detail view of 15 the cutter and shoe; and Fig. 4 is a similar view of the anchor.

Similar letters of reference indicate corresponding parts in all the figures.

My invention has relation to machines for 20 cutting ditches for laying tiles; and it consists in the improved construction and combination of parts of the same, as hereinafter more fully described and claimed.

In the accompanying drawings, the letter A 25 represents a rectangular frame mounted upon wheels, and having uprights B, upon which a similar frame, C, is mounted. In the center of these frames is formed an upright square frame, by uprights D, between the frames, and 30 by cross-pieces E, between the side pieces of the frames, in which slides a rectangular cage, F, in which the cutter and capstan are journaled. This cage may be raised and lowered at will by means of a windlass, G, journaled in bearings 35 upon two cross-pieces, H, fastened between the uprights D, upon which windlass two ropes or chains, I, fastened to the top and bottom of the cage, are wound, while it is operated by means of a crank at one end and held fast at any point 40 by means of a strap, J, passing over and bearing against the flat rim of a wheel, K, upon the axle of the windlass, acting as a brake.

The machine is propelled by means of a rope or chain, L, fastened to the front end of the 45 machine, passed over a pulley, M, upon a portable anchor, N, and fastened at its other end to a capstan, O, journaled vertically in the center of the cage and operated by a sweep, P, fastened to its upper end, which projects up

through the top of the cage, and to which sweep 50 one or more draft-animals are hitched.

An inwardly-beveled cog-wheel, Q, is fastened upon the upper end of the capstan, above the top of the frame and below the sweep, and intermeshes with a beveled pinion, R, fastened 55 upon the upper end of the shaft S of the cutter T, rotating it while winding the rope.

The cutter T consists of two or more spirally wound cutting-flanges, U, which are cut obliquely off toward the center at their lower end, 60 forming a boring-point, and it is rotated inside a semi-cylindrical shoe, V, fastened in the rear of the cutter, downwardly projecting from the lower end of the cage, and supported by an oblique brace, W, also fastened to the lower 65 end of the cage. A semicircularly-bent plate, X, having two flaring oblique wings, Y, is placed around the upper portion of the shoe, and held in place by two bars or rods, Z, fastened to the lower front edge of the cage, and serves to throw 70 the dirt, as it is screwed up by the cutter, between the latter and the shoe, to both sides of the ditch thus formed.

Upon one of the side pieces of the upper frame, C, is fastened a plumb-level, a, consisting 75 of a loaded pendulum, b, pointing upon a segmental scale, c, which is divided and numbered in such a manner as to indicate the rise in a certain distance—as, for instance, the rise in feet to the rod—and a finger, d, projecting from 80 the side piece of the frame C, points upon a scale, e, upon the adjoining upright, f, of the cage, indicating at what depth the cutter is working, so that the cage, and with it the cutter, may be raised or lowered by means of the 85 windlass, according to the indications of the pendulum.

A flat board or bridge, g, is hinged to the rear of the bridge by means of chains or hooked rods h, and is dragged along with the machine, 90 serving as a crossing for the draft-animals over the ditch.

The propelling rope or chain L is, as before mentioned, fastened to the front end of the machine, preferably to the forward-turned hounds 95 i of the swiveled front truck, and passes over the pulley M upon the anchor N. This anchor consists of a frame, j, mounted upon rollers or

wheels *k* in the front part, and having two pointed arms hinged to its sides, adapted to enter the ground obliquely and rearwardly, being prevented from turning under the frame by 5 two bails, *l*, fastened to the frame and passing around the arms, which thus hold the anchor firmly upon its place. In returning from the pulley *M* the rope passes through an eye or pulley, *m*, upon the hounds of the front truck and 10 around the capstan. It will thus be seen that as the sweep is rotated by the draft-animals the machine is drawn toward the anchor, which previously has been placed at the end of the line to be ditched, cutting the ditch and throwing 15 the dirt up on both sides of the ditch, and that by the machine being provided with the swinging pendulum, the gage upon the side of the cage, and means for raising and lowering the cutter, the depth of the ditch may be regulated according to the rise and fall of the surface by a person standing upon the machine 20 operating the windlass.

Having thus described my invention, I claim and desire to secure by Letters Patent of the 25 United States—

1. In a ditching-machine, the combination of the capstan *O*, having inwardly-beveled cog-

wheel *Q*, cutter *S* *T*, having beveled pinion *R*, shoe *V*, and winged curved plate *X* *Y*, all journaled in and fastened to the cage *F*, having 30 means for raising and lowering it, as and for the purpose shown and set forth.

2. In a ditching-machine, the combination of the cage *F*, sliding in upright frame *D* *E*, windlass *G*, having ropes or chains *I*, capstan *O*, 35 having inwardly-beveled cog-wheel *Q*, cutter *S* *T*, having beveled pinion *R*, shoe *V*, and winged curved plate *X* *Y*, as and for the purpose shown and set forth.

3. The combination, in a ditching-machine, 40 of the cage *F*, forming bearings for the propelling-capstan and the cutter, and having scale *e* upon one of its uprights, with the frame *A* *B* *C* *D* *E* *H*, having plumb-level *a* and finger *d*, and the windlass *G*, having chains *I*, 45 flat-rimmed wheel *K*, and brake-strap *J*, as and for the purpose shown and set forth.

In testimony that I claim the foregoing as my own I have hereunto affixed my signature in presence of two witnesses.

HENRY H. EATHERTON.
